UNITED STATES PATENT OFFICE.

WALTER C. WESTAWAY AND LEWIS W. BEARD, OF DECORAH, IOWA.

MECHANICAL MOVEMENT.

SPECIFICATION forming part of Letters Patent No. 432,586, dated July 22, 1890.

Application filed February 21, 1890. Serial No. 341,336. (No model.)

To all whom it may concern:

Be it known that we, WALTER C. WESTAWAY and LEWIS W. BEARD, of Decorah, in the county of Winneshiek and State of Iowa, have invented certain new and useful Improvements in Mechanical Movements; and we do hereby declare the following to be a full, clear, and exact description of the invention, such as will enable others skilled in the art to which it appertains to make and use the same.

Our invention relates to an improvement in mechanical movements applicable to various machines when the end to be attained is the conversion of rotary motion to reciprocating or reciprocating motion to rotary, and in the practical embodiment of this invention it is illustrated in connection with a windmill.

The primary object is to concentrate the power derived from two or more revolutions of a suitable rotary device into a single thrust of a reciprocating rod; and to this end our invention consists in a rotary shaft having a spiral cam thereon and connected gearing for communicating motion from the shaft to other parts of the mechanism, in combination with a vibrating lever, a reciprocating rod, a bearing wheel or roller connected with the lever for following the spiral cam, whereby the lever is raised, and means for throwing this bearing wheel or roller out of contact with the spiral cam to lower the rod and to resume a proper position to again travel up the incline afforded by the spiral cam, and thereby raise the rod.

Our invention further consists in certain novel features of construction and combinations of parts, as will be hereinafter described, and pointed out in the claims.

In the accompanying drawings, Figure 1 is a sectional view through the frame-work of a windmill, showing our improved mechanical movement applied thereto, parts being in section and parts in elevation. Fig. 2 is a detached view of the swinging lever. Fig. 3 is a section on line $\alpha\alpha$ of Fig. 1. Fig. 4 is an enlarged detached view of the spiral cam-wheel, and Fig. 5 is a similar view of a gear-wheel having a cam-flange thereon.

A represents a rotary shaft journaled in bearings 11 in a suitable frame-work, of

which the mechanism constituting the present invention is a part.

For the purpose of illustration and a practical embodiment of the invention it is shown in connection with a windmill, the frame being the frame of this windmill, having the wheel secured on one end of the shaft and the vane pivoted at points 22 on the frame. Keyed or otherwise secured on the rotary drive-shaft A is a spiral cam-wheel 3, which is mainly instrumental in effecting the conversion of motion from rotary, as described by itself and the shaft upon which it is mounted, to reciprocating. A long arm or lever 4 is pivoted at one end 5 to the framework, and thence passing through a slot formed for it in the upper portion of the frame it extends forward in the same vertical plane with the shaft, and at its opposite end is pivotally secured to the upper end of the rod 6, which operates the pump. A depending hanger 7 is pivoted to the swinging lever 4, and an L-shaped arm 8, also pivotally supported on lever 4, terminates at one end in a horizontal shaft 9, passes through openings formed for it in the lower end of the hanger 7, and forms an axle for the bearing-wheel 10. The latter travels on the spiral cam 3, and by its combined contact therewith and the rotation of the shaft A the lever 4 is raised, carrying with it the rod 6. Thus one motion is given to the rod. The opposite motion is produced by other mechanism now to be described. A gear-wheel 12 is revolvably supported on the bearing 13, and the teeth of this wheel are meshed with the teeth of pinion 14, by which it is driven, and the latter may be simply keyed on the horizontal shaft A, or it may be formed integral with the hub 90 of the spiral cam. This gear-wheel is provided on an inner face with a cam offset 15, which the lower end of the L-shaped arm 8 engages. This offset is eccentrically arranged around the center and is in two or more planes, and the wheel is so geared relative to the other parts, especially the spiral cam and the L-shaped arm 8, that it makes one revolution to three of the spiral cam, in order to remove the bearing-wheel from the spiral cam, and thus drop the lever 4, with the attached rod, preparatory to traveling again on

the spiral. In the drawings attached the spiral cam is driven two full revolutions to make the upstroke of the rod complete, while it is carried back to the starting-point with 5 one revolution of the shaft A, and in this case the wheel 12 is three times the diameter of the pinion 14. In this way the rod is continually raised and lowered, the lever 4, which carries the rod, being raised by the spiral cam 10 and carried back by a positive motion transmitted from the cam-offset 15 by means of the L-shaped arm 8. The number of revolutions of the spiral cam to make an upward stroke of the rod may be varied to suit the 15 work by making as many steps or turns on the spiral as there are revolutions needed and timing the pinion and gear-wheel carrying the cam-offset to match. The rod and also the lower end of the L-shaped arm are 20 split or slotted so as to straddle the shaft A for the purpose of forming a guide for them in their movements.

It is evident that slight changes might be resorted to in the form and arrangement of 25 the several parts described without departing from the spirit and scope of our invention, and hence we do not wish to limit ourselves to the exact construction herein set forth; but,

30 Having fully described our invention, what we claim as new, and desire to secure by Letters Patent, is—

1. The combination, with a rotary spiral cam and a rod, of a rotary bearing-wheel 35 adapted to travel on the cam, and cam for automatically throwing the rotary bearing-wheel out of contact with the spiral cam, substantially as set forth.

2. The combination, with a rotary spiral 40 cam and a rod, of a rotary bearing-wheel connected with the rod and having contact with the spiral cam, a gear-wheel having a cam-offset on its side, said wheel being driven by a wheel adjacent to the spiral cam, and an L-shaped arm, one end of which forms a bearing 45 for the rotary bearing-wheel and the other end having engagement with the cam-offset,

whereby the bearing-wheel is thrown in and out of engagement with the spiral cam to raise or lower the rod, substantially as set forth. 50

3. The combination, with a rotary spiral cam and swinging arm, of a bearing-wheel depending from the arm and a rod connected with this arm and adapted to be reciprocated by the swinging arm substantially as set forth. 55

4. The combination, with a rotary spiral cam and a swinging arm, of a depending hanger pivoted to this lever, an arm pivoted to the swinging arm and passing loosely through the hanger, a wheel or roller within the hanger 60 revolvably supported on the arm and adapted to bear on the spiral cam, and a rod pivotally connected with the outer end of the lever, substantially as set forth.

5. The combination, with a frame, a rotary 65 shaft, and spiral cam secured on the shaft, of a swinging arm having a rod pivotally connected therewith and a depending hanger pivoted to the lever and having a bearing wheel or roller adapted to travel on the spiral cam, whereby the lever is swung and the rod is moved endwise, substantially as set forth. 70

6. The combination, with a frame, a rotary 75 shaft and a spiral cam and pinion thereon, of a swinging arm having a rod pivoted to its outer end, a bearing wheel or roller depending from the lever in position to travel on the cam, a gear-wheel meshed with the pinion, said wheel having a cam-offset on one face, and an L-shaped lever pivoted to the swinging lever, one end forming an axis for the bearing wheel or roller and the other having engagement with the cam-offset, whereby the bearing wheel or roller is automatically shifted, substantially as set forth. 80

85 In testimony whereof we have signed this specification in the presence of two subscribing witnesses.
